GEORGE RUDOLPH METTEN, OF ST. LOUIS, MISSOURI, ASSIGNOR TO
HORACE BALDWIN, OF PAINESVILLE, OHIO.

Letters Patent No. 70,453, dated November 5, 1867.

FOUNTAIN PEN.

The Schedule referred to in these Letters Patent and making part of the same.

TO ALL WHOM IT MAY CONCERN:

Be it known that I, GEORGE RUDOLPH METTEN, of St. Louis, in the county of St. Louis, and State of Missouri, have invented a new and improved Fountain Pen; and I do hereby declare that the following is a full, clear, and exact description thereof, reference being had to the accompanying drawings, making a part of this specification, in which—

Figure 1 is a diametrical section through the improved fountain pen.

Figure 2 is an enlarged view of the supply tube and pen detached from the handle or fountain.

Figure 3 is a sectional view of the elastic ink holder.

Figure 4 shows the invention applied to an extensible handle..

Figure 5 is an enlarged sectional view of the end of the supply tube and its valve.

Similar letters of reference indicate corresponding parts in the several figures.

This invention relates to certain novel improvements on writing pens, which are constructed with elastic or flexible sacks in hollow holders or handles for containing the writing ink, and also with a provision for causing the ink to flow to and supply the pen during the act of writing.

The first part of my invention consists in the employment of an elastic or flexible tube or reservoir within a hollow penholder for containing the ink, and in so applying such reservoir that it will cause a free flow of ink to the pen in the act of writing, and at the same time keep the ink in the reservoir free from air, as will be hereinafter described.

To enable others skilled in the art to understand my invention, I will describe its construction and operation.

In the accompanying drawings, fig. 1, *a* represents the main handle or holder, which may be constructed of metal or other suitable material, and which has a cap, *a'*, screwed upon one end, through which cap a hole is made for the admission of air into the holder. Within this hollow holder is a flexible ink sack or fountain, *b*, which I prefer to make of India rubber, and which is secured in place at its open end by means of a small ring, *c*, as shown. This sack *b* is not quite as long as the holder containing it, and is thus made for the purpose of having a tubular and shouldered-sheath, *d*, screwed into the open end of the holder, as shown in the drawings, which sheath serves, in conjunction with the upper portion of the supply tube *e*, to form a receptacle, and a means for receiving and holding the pen *f*. The supply tube *e* is screwed into the sheath *d*, so as to be firmly and tightly secured to the handle *a*, and so as to conduct ink from the reservoir or elastic sack *b* to the pen. The outer end of this supply tube *e* terminates in a slightly curved portion, *e'*, in which a valve, *g*, is nicely fitted so as to be pressed upon by the pen, when not in use, and thereby held firmly down upon its seat.

When the instrument is used the pressure upon the point of the pen will, to a greater or less extent, relieve the pressure upon said valve, and thus allow the ink to escape upon the pen.

In fig. 5 a thin packing, *h*, is represented as applied to the valve for more effectually closing the supply vent when the pen is not in use.

When the instrument, which I have above described, is not in use, the sliding tube *A*, upon the outside of the handle *a*, is drawn over the pen so as to protect it from injury.

In fig. 4 I have represented my invention applied to a tube, which is fitted into a hollow handle in such manner as to form an extensible holder. That portion of the instrument to which the pen, supply tube, and fountain sack are applied, can be pressed into the holder or sheath so as to enclose and protect the pen when not in use.

It will be seen from the above description that the ink is contained within an elastic and flexible sack, so as to be free from contact with the air, said sack being enclosed within a holder, into which air is allowed to enter so as to compress the sack and cause it to collapse as the ink flows from it. Thus it will be seen that while the ink is fully protected from escaping from the sack, except at the proper point, there will be no vacuum to obstruct its flow to the pen, the atmosphere being allowed to press freely upon all sides of the ink-sack without affecting the condition of the ink contained therein.

The elastic pressure of the pen upon the valve, which is applied to the orifice of the supply tube, will, when

the pen is not in use, keep this orifice closed, and, when the pen is in use, this pressure will be more or less removed so as to allow a free flow of the ink, in accordance with the force and rapidity of the strokes.

I do not desire to confine my invention to the precise construction of the supplying tube, as other means, operating substantially upon the principle herein described, may be adopted. I prefer, however, the use of the contrivance described for conducting the ink to the pen.

The supply tube *e* is provided with a filtering substance, such as sponge or pumice-stone, for the purpose of arresting any sediment which might be in the ink-sack, and preventing the clogging up of the fine opening or passage leading to the valve-chamber.

Having described my invention, what I claim as new, and desire to secure by Letters Patent, is—

1. In combination with an air-tight and flexible ink-sack, which is applied within the handle or holder of a fountain pen, so as to be free to collapse as the ink flows from it, I claim a tube, *e*, which extends beneath the pen *f*, and is provided with a valve, *g*, at the point of discharge, so that in the act of writing the ink shall be caused to flow to the pen with greater or less freedom, according to the force and rapidity of the strokes, substantially as specified.

2. A fountain pen, which is provided with a thin, air-tight, flexible sack, applied within the pen-handle or holder by means of a ring, *c*, in combination with a removable pen-sheath, *d*, and supply tube *e*, substantially as described.

3. In combination with the flexible sack *b* and ink supply-tube *e*, I claim the conical valve or plug *g*, acting as a regulator during the act of writing, and serving to close the aperture when there is no pressure applied to the nib of the pen, substantially as described.

G. R. METTEN.
